UNITED STATES PATENT OFFICE

100,590

DESIGN FOR A SOCKET SUPPORT FOR CHANDELIERS

Edgar A. Wangersheim, Chicago, Ill.

Application June 10, 1936, Serial No. 63,188

Term of patent 3½ years

To all whom it may concern:

Be it known that I, Edgar A. Wangersheim, a citizen of the United States, residing at Chicago, in the county of Cook and State of Illinois, have invented a new, original, and ornamental Design for a Socket Support for Chandeliers, of which the following is a specification, reference being had to the accompanying drawing, forming part thereof.

I claim:

The ornamental design for a socket support for chandeliers, as shown.

EDGAR A. WANGERSHEIM.
